UNITED STATES PATENT OFFICE

158,651

JEWELRY CASE

Herbert Chase, New York, N. Y., assignor to
Bernard Cahn Co. Inc., New York, N. Y., a corporation of New York

Application June 10, 1949, Serial No. 3,194

Term of patent 7 years

(Cl. D58—2)

To all whom it may concern:

Be it known that I, Herbert Chase, a citizen of the United States, residing at city of New York, county of Queens, and State of New York, have invented a new, original, and ornamental Design for a Jewelry Case, of which the following is a specification, reference being had to the accompanying drawing forming a part hereof.

In the drawing:

Fig. 1 is an inside plan view of a jewelry case showing my new design, the case being shown in fully opened position.

Fig. 2 is an outside plan view thereof.

Fig. 3 is a perspective view thereof shown in partly closed position.

Fig. 4 is a front elevational view of the same in a closed condition.

Fig. 5 is a side elevational view of the same in a closed condition.

I claim:

The ornamental design for a jewelry case, substantially as shown.

HERBERT CHASE.
